UNITED STATES PATENT OFFICE.

WILLIAM S. TUCKER, OF MYRTLEWOOD, ALABAMA.

SMOKE-CONSUMER.

1,113,070.

Specification of Letters Patent.

Patented Oct. 6, 1914.

Application filed December 3, 1913. Serial No. 804,471.

To all whom it may concern:

Be it known that I, WILLIAM S. TUCKER, a citizen of the United States, residing at Myrtlewood, in the county of Marengo and State of Alabama, have invented new and useful Improvements in Smoke-Consumers, of which the following is a specification.

The invention has relation to smoke consuming furnaces, the purpose being to utilize the fuel so as to obtain a maximum amount of heat units and to prevent the giving off of smoke, free carbon and gases.

The invention provides a furnace of the nature hereinbefore stated which will convert the products of combustion into a gas which later is consumed and utilized as the direct heating means for raising the temperature of water or converting the same into steam.

20 The invention consists of the novel features, details of construction and combination of parts, which hereinafter will be more particularly set forth, illustrated in the accompanying drawing, and pointed out in the appended claims.

Referring to the drawing, forming a part of the specification, Figure 1 is a central longitudinal section of a smoke consuming furnace embodying the invention. Fig. 2 is 30 a horizontal section on the line $x-x$ of Fig. 1. Fig. 3 is a longitudinal section of the smoke consuming apparatus to be adapted to any make or variety of furnace. Fig. 4 is a horizontal section on the line $y-y$ of Fig. 3.

Corresponding and like parts are referred to in the following description, and indicated in all the views of the drawing, by the same reference characters.

40 Inasmuch as the invention is primarily designed for furnaces of the horizontal tubular type, it is shown in connection with a furnace of such variety. The appliance embodies a combustion chamber 1, a smoke space 2, a gas chamber 3 and a tube 4 through which the smoke and products of combustion pass and are heated in their travel to convert the same into a gaseous form which after leaving the chamber 3 is 45 burned to produce the required heat. The appliance may be built in to a furnace as a part thereof or may be constructed separately in the nature of an attachment to be fitted to any style of furnace to be equipped 50 with a smoke consuming device. As indicated in the drawings the furnace embodies

a plurality of horizontal flues 5 through which the flame and hot air pass so as to heat the water surrounding such flues and in contact therewith. The rear portion of the furnace contains the smoke consuming device which embodies a shell or casing 7 the top of which is in contact with or may form the crown shape of the furnace proper. A partition 8 divides the upper portion of the shell or casing and forms the smoke space 2 and the combustion chamber 1. The fuel is adapted to be consumed in the lower portion of the combustion chamber 1 in the manner well understood and the smoke and gases arising therefrom pass into the space 2 through an opening 9 formed in the partition 8 near one end thereof, a cut-off 10 is provided to regulate the effective size of the opening 9. The tube 4 communicates with the opposite end of the smoke space 2 and extends through the combustion chamber over the fire and connects with the vertical wall 11 separating the gas chamber 3 from the combustion chamber 1 and smoke space 2. The smoke and gases in their passage through the tube 4 are gasified and are at the same time retarded, the latter resulting from the formation of the tube 4 which tapers throughout its length. It is to be understood that it is contemplated to provide a plurality of tapered tubes 4 thereby distributing the smoke and gases and providing an extended heating surface for gasifying the same. An opening 12 is formed in the bottom of the gas chamber 3 near the vertical wall 11 and provides an escape for any accumulation of ashes, unconsumed cinders or other particles. The opening 12 is controlled by means of a slide 13. An outlet 14 is provided for each flue 5 and constitutes a burner for consumption of the gas escaping from the chamber 3. The burner outlets 14 are arranged to direct the flame into the flues 5 so as to heat the water surrounding and in contact with such flues.

When a boiler furnace has a smoke consuming device installed therein in accordance with the principles of the present invention the operation of the same is as follows: The fuel is placed in the lower portion of the combustion chamber 1 and is ignited in any well known manner. The smoke and products of combustion resulting pass through the opening 9 into the space 2 and are heated and after leaving the space 2 the smoke and gases pass through the tube

or tubes 4 and are further heated and gassified and at the same time compressed by reason of the gradual reduction of the passage through the tube or tubes 4. The gas 5 after leaving the tube 4 enters the chamber 3 and passes out through the burner outlets 14 and is ignited and consumed in a manner well understood. The discharge ends of the tube or tubes 4 project slightly 10 into the gas chamber 3 beyond the wall 11 and curved downward so as to deflect cinders or other particles to the bottom of the gas chamber where they collect to be removed from time to time through the opening 15 12 which is uncovered by proper adjustment of the slide 13.

From the foregoing description, taken in connection with the accompanying drawing, the advantages of the construction and 20 of the method of operation will be readily apparent to those skilled in the art to which the invention appertains, and while I have described the principle of operation of the invention, together with the device which 25 I now consider to be the best embodiment thereof, I desire to have it understood that the device shown is merely illustrative, and that such changes may be made when desired as are within the scope of the claims 30 appended hereto.

What I claim as new, is:—

1. A smoke consuming appliance comprising a shell or casing embodying a gas chamber at one end a combustion chamber and a 35 smoke space above the combustion chamber and in communication therewith at one end and a tube connected with the opposite end of the smoke space and extending through the combustion chamber over the 40 fire and connecting with the gas chamber.

2. A smoke consuming appliance comprising a shell or casing, a gas chamber at one end and a combustion chamber and smoke space at the opposite end, the smoke space 45 being arranged above the combustion chamber and in communication therewith near the gas chamber and a tapered tube extending through the combustion chamber over the fire therein and connecting at its larger 50 end with the opposite end portions of the smoke space and at its smaller end with the gas chamber.

3. A smoke consuming appliance comprising a shell or casing embodying a gas chamber at one end having a burner outlet and a 55 combustion chamber and smoke space at the opposite end, said smoke space being located above the combustion chamber and having communication therewith near the gas chamber, a cut-off for regulating the 60 communication between the combustion chamber and smoke space and a tapered tube extending through the combustion chamber over the fire therein and connecting at its smaller end with the gas chamber and at its 65 larger end with the before mentioned smoke space at the end remote from the gas chamber.

4. A smoke consuming appliance comprising a shell or casing having a gas chamber 70 at one end providing a burner outlet and a damper controlled outlet for unconsumed particles and a smoke space and combustion chamber at its opposite end said smoke space being located above the combustion chamber 75 and in communication therewith near the gas chamber, a cut-off for regulating the opening between the combustion and smoke space and a tapered tube extending through the combustion chamber and connected at its 80 smaller end with the gas chamber and at its larger end with the smoke space at the end remote from the gas chamber.

5. In a smoke consuming appliance, a shell or casing embodying a gas chamber 85 and a combustion chamber and smoke space at one side of the gas chamber with the smoke space above the combustion chamber and in communication therewith at one end, said gas chamber having a damper controlled outlet, and a tube extending through the combustion chamber over the fire therein and connecting the smoke space with the gas chamber the delivery end of such tube being deflected to cause unconsumed particles to be thrown to the bottom of the 90 gas chamber.

In testimony whereof I affix my signature in presence of two witnesses.

WILLIAM S. TUCKER.
